ALLEN S. APGAR, OF NEW YORK, N. Y., ASSIGNOR TO HIMSELF AND ISAAC ARNOLD JR., OF HADDAM, MASSACHUSETTS.

Letters Patent No. 101,207, dated March 29, 1870.

IMPROVEMENT IN SCREW AND SCREW-DRIVER.

The Schedule referred to in these Letters Patent and making part of the same

To all whom it may concern:

Be it known that I, ALLEN S. APGAR, of the city county, and State of New York, have invented certain new and useful Improvements in the Manufacture of Wood or Metal Screws, for screwing into wood or metal, and Screw-Drivers for holding and turning said screws into the wood or metal; and to enable others skilled in the art to make and use the same, I will proceed to describe, referring to the drawings, in which the same letters indicate like parts in each of the figures.

The nature of this invention consists in forming an angular slit in one side and near the base of the nick of a wood or metal screw, the object of which is to firmly hold the screw-driver in the nick of the screw, and in a straight line, or nearly so, therewith, so that a screw placed upon the end of the driver will be held, and may be inserted at a distance where it would be difficult to place a screw by hand.

In the accompanying drawings—

Figures 1 and 2 are side views, one showing the driver inserted into the nick and slit of the screw.

a is the wood or metal screw.

b is the head of the screw.

c is the nick of the screw.

This screw as thus far described is constructed like those in common use.

d is a slit cut in the side of and near the base of the nick *c*.

e is a screw-driver.

f is the screw-driver handle, both made in the common way, except that a side projection or hook formation, *h*, is made on one side and near the end thereof, so that, by placing the bent portion *h* into the nick *c* of the screw, while the handle or driver is held at an angle of about forty-five degrees with the screw, by turning the driver from this point into a straight

line with the screw, the projection or hook *h* will enter the slit *d*, and hold the driver firmly in the nick of the screw, until it, the screw, has been inserted and screwed to its place, when, by turning the driver back into the angle required for its insertion into the nick, it can be easily and quickly removed therefrom. Thus the screw may be held steadily upon the end of the driver, (see fig. 2,) and inserted into a place which would be difficult to reach by hand.

It will be seen that when the driver is inserted into the nick and slit of the screw thus constructed, it cannot be pulled or withdrawn therefrom, except when placed at about the same angle as when it was inserted, or, in other words, it cannot be pulled therefrom in a straight line with the screw, but can be easily and quickly removed and replaced by bringing it at a proper angle out of a straight line with the screw, which it is believed cannot be accomplished by any other construction of the screw and driver heretofore known or used.

I believe I have thus shown the nature, construction, and advantage of this invention, so as to enable others skilled in the art to make and use the same therefrom.

What I claim, therefore, and desire to secure by Letters Patent, is—

1. A nick-slotted screw, *c d a*, substantially as set forth.
2. The driver *e*, as described, for the purpose of holding, inserting, and screwing it to its place, substantially as set forth.

ALLEN S. APGAR. [L. S.]
